UNITED STATES PATENT OFFICE

ELWOOD W. MCINTIRE, OF VENTNOR, NEW JERSEY

ATTACHMENT FOR IRONING BOARDS

Application filed July 20, 1929. Serial No. 379,783.

This invention relates to an attachment for ironing boards, the attachment being in the nature of a device for holding the iron on the board in an out of the way manner, yet 5 to permit of convenient access to the iron.

A further object of the invention resides in the provision of an attachment of this nature, consisting of a bracket member adapted to be fixed to the ironing board and an iron 10 holding member in the form of a frame slidably supported on the first mentioned member between the member and the bottom face of the board, and the inner end of the frame holding member adapted to abut the under- 15 face of the board when the iron is placed on that end of the frame projecting beyond the board.

A still further object of the invention resides in the provision of an iron holding attachment for ironing boards which is simply 20 constructed, strong, durable, inexpensive to manufacture, thoroughly reliable practical and efficient in use.

Other objects and advantages of the invention 25 will become apparent during a study of the following description, taken in connection with the following drawings, wherein:

Figure 1 is a top plan view of my attachment showing the application of the same to 30 an ironing board, the ironing board being shown fragmentarily.

Figure 2 is a vertical longitudinal sectional view taken substantially on line 2-2 of Figure 1.

Figure 3 is a transverse sectional view 35 taken substantially on line 3-3 of Figure 1.

With reference more in detail to the drawings, it will be seen that I have denoted generally by the reference character 5 an iron- 40 ing board of conventional construction, one end of which board is provided with my iron holding attachment.

That form of my invention as herein illustrated consists in a rigid supporting bracket designated generally by the reference character 6, said bracket being formed of an elongated strip of metal of suitable length bent upwardly at right angles at its opposite ends as at 7 and then bent laterally to provide 45 a pair of attaching ears 8-8.

The attaching bracket 6 is disposed transversely of the ironing board 5 adjacent one end of the ironing board so that the intermediate or body portion of the bracket is disposed in spaced relation to the board 5 55 and suitable fastening elements such as screws 9 are passed through the apertured ears 8 and screwed into the board 5 for rigidly maintaining the bracket 6 in a rigid position and in spaced relation to the under- 60 surface of the board as clearly suggested in Figure 3.

The attachment further comprises an iron holding frame designated generally by the reference character 10. The iron holding 65 frame comprises a transverse bar 11 bent upwardly or at right angles at its opposite ends as at 12, while secured to this bar and arranged in longitudinal spaced relation on said bar 11 is a plurality of bars 13, each of 70 which bars is secured adjacent one end as at 14 to the bar 11 so as to extend laterally with respect to the bar 11.

As shown to advantage in Figure 1, the bars 13 graduate in size, the longer of the 75 bars being at one end and the shortest of the bars being at the other or opposite end of the bar 11. At their attached ends, the bars 13 have their terminals bent upwardly at right angles as at 15. The center or intermediate 80 bar 13 is bent upon itself intermediate its ends and adjacent to its attached end to provide a stop 16.

When the supporting bracket 6 is placed in position upon the ironing board 5 in a 85 manner as before described the forward or flat ends of the bars 13 of the iron supporting frame 10 are passed between the body of the bracket 6 and the board 5 as suggested in Figure 1, the stop member 16 of the intermediate bar 13 abutting the outer edge of the board 5 to limit the inward movement of the iron supporting frame 10.

That portion of the frame now projecting beyond the said end of the ironing board 95 5 provides a suitable supporting surface for an iron, and it will be noted that the bars graduating in size as mentioned will conform somewhat to the contour of the iron and the terminals 15 of the bars 13 and terminals 12 100

of the bar 11 will provide stops for the iron in an obvious manner.

From the foregoing it will be seen that I have provided a simple, inexpensive attachment for ironing boards for holding the iron at one end of the board in a secure and positive manner and in an out of the way, yet readily accessible position.

Even though I have herein shown and described in detail the preferred embodiment of my invention, it is to be understood that the same is susceptible to changes in size, arrangement of the separate parts, materials used and other such details as come within the spirit of the invention as herein described, and the scope of the appended claims.

Having thus described my invention, what I claim as new is:

1. In combination with an ironing board, an elongated bracket member secured to the ironing board at one end thereof, said bracket member having its intermediate portion disposed in spaced relation to the board, and an iron supporting frame comprising a bar, a plurality of bars secured to the first mentioned bar and extending laterally on both sides of said bar, said latter bars at the ends on one side of the first mentioned bar being slidably engaged with the bracket and positioned between said bracket and the board, a pair of gripping fingers formed on the opposite end of the first mentioned bar, a gripping finger formed on each of the other of said bars at the ends opposite to the first mentioned ends, one of said last mentioned bars being provided intermediate its ends and between the first bar and the first mentioned end with a stop adapted for engagement, with the ironing board to limit the inward sliding movement of the iron supporting frame upon said bracket.

2. In combination with an ironing board, an elongated bracket member secured to the ironing board at one end thereof, said bracket member having its intermediate portion disposed in spaced relation to the board, and an iron supporting frame comprising a bar, a plurality of bars secured to the first mentioned bar and extending laterally on both sides of said bar, said latter bars at the ends on one side of the first mentioned bar being slidably engaged with the bracket and positioned between said bracket and the board, a pair of gripping fingers formed on the opposite end of the first mentioned bar, a gripping finger formed on each of the other of said bars at the ends opposite to the first mentioned ends, one of said last mentioned bars being provided intermediate its ends and between the first bar and the first mentioned end with a stop adapted for engagement with the ironing board to limit the inward sliding movement of the iron supporting frame upon said bracket, and said last mentioned bars graduating in size from one

end to the other of the first mentioned bar.

3. In a holder for sad irons, a bracket adapted to be secured to a support, said bracket having an intermediate portion in spaced relation to the support, a plurality of spaced elongated bars, a cross bar connecting the first mentioned bars, adjacent one end of said spaced bars, said spaced bars having their opposite end portions slidable on the intermediate portion of said bracket, between said bracket and the support, in a horizontal plane, said spaced bars at said first mentioned one end provided respectively with an upstanding sad iron engaging finger, and said cross bar at its opposite ends being provided with upstanding sad iron engaging fingers.

In testimony whereof I affix my signature.

ELWOOD W. McINTIRE.
